UNITED STATES PATENT OFFICE

2,373,522

VALVE GRINDER

James A. Williams, Sr., Belfast, Tenn.

Application January 28, 1944, Serial No. 520,084

1 Claim. (Cl. 51—29)

This invention relates to new and useful improvements in valve grinders and more particularly to a grinder adapted to be powered by vacuum, the principal object being to provide a valve grinder operated by a vacuum motor such as is at present employed on automobiles for operating windshield wipers.

An important object of the present invention is to provide a grinder which is of simple construction and which will alleviate to a considerable extent the effort mechanics must now expend in the operation of the grinding valves.

Other objects and advantages of the invention will become apparent to the reader of the following description.

In the drawings:

Figure 1 represents a side elevational view of the device.

Figure 2 is a fragmentary top plan view.

Figure 3 is a vertical sectional view through the device.

Figure 4 is a transverse section taken on the line 4—4 of Figure 1.

Figure 5 is a fragmentary detailed sectional view showing a suction type of contact head.

Figure 6 is a fragmentary detailed sectional view showing one form of valve engaging element.

Figure 7 is a side elevational view of a valve return spring.

Figure 8 is a side elevational view with a portion in section showing another form of valve engaging element.

Referring to the drawings wherein like numerals designate like parts, it can be seen that reference character A denotes a frame having top and bottom portions 5, 6, a handle interposed between the top and bottom portions at the rear ends thereof and denoted by numeral 7, and a front portion 8. Forward and rearward vertical cross members 9, 10 are provided in the frame. Mounted on the cross member 10 is an oscillating vacuum operated motor 11 for operating a shaft 12. This shaft extends into a coupling sleeve 13 and is connected thereto by a cotter key 14. The sleeve 13, in turn, extends over the reduced end of a counter-shaft 15 and is secured

to said counter-shaft by a cotter key 16. The counter-shaft 15 carries a gear 17 which meshes with a pinion 18 on a tool shaft 19 which is journaled through the front portion 8 of the frame A and the cross member 9. A screw 20 is disposed through a shoulder portion 21 of the top portion 5 of the frame and serves as a thrust bearing for the tool shaft 19. The outer end of the tool shaft 19 has a diametrical opening 22 for receiving a cotter key 23 for securing anyone of the valve head engaging tools 23, 24 or 25 to the shaft 19. It can be seen that the tools 23 and 24 each has a socket and a blade, the blades being so formed as to engage the correspondingly constructed valve heads and each socket has an opening for alignment with the opening 22 to accommodate the cotter key 23.

The valve head engaging tool 25 is in the form of a rubber suction cup 26 for use with valve heads which are smooth.

Numerical 27 denotes a coiled compression spring for returning the valve from the seat.

Obviously, when the motor 11 is connected by a hose 28 to a suction means such as the intake of a motor, the motor will oscillate the shaft 12 and, in turn, transmit a corresponding motion to the tool shaft 19, with the result that the valve is ground by oscillatory motion.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A valve grinder comprising a frame, a handle on the frame, a motor mounted within the frame, a drive shaft driven by the motor, a tool shaft journaled to the frame and gear means between the shafts, and a screw defining a thrust bearing for the tool shaft, said screw being adjustably disposed through a portion of the frame to engage the inner end of the tool shaft, said motor being vacuum operative to oscillate the drive shaft.

JAMES A. WILLIAMS, SR.
